UNITED STATES PATENT OFFICE.

EDWIN L. NELLIS, OF ALLENTOWN, PENNSYLVANIA, ASSIGNOR TO TROJAN POWDER COMPANY, OF NEW YORK, N. Y., A CORPORATION OF NEW YORK.

MANUFACTURE OF NITRIC ACID.

Application filed October 29, 1921. Serial No. 511,264.

This invention relates to improvements in the manufacture of nitric acid.

In the usual process of making nitric acid, sodium nitrate and sulfuric acid are heated together in a retort, and the distillate is condensed. This distillate varies in composition at different periods during the time of heating, the first and last portions of the distillate from each run being relatively weak, while the main quantity of the distillate is approximately 97% HNO_3 . This weakness of the first and latter portions of the distillate is due to the water introduced into the retort with the nitrate of soda and with the sulfuric acid, this water passing over and diluting the nitric acid of the distillate. The amount of water in the nitric acid as it distills over varies with the amount of water introduced into the retort with the nitrate of soda and the sulfuric acid and with the intensity of the fire under the retort, and also to a great extent with the amount of the sulfuric acid, an excess of sulfuric acid having a tendency to hold the water and prevent its going over into the condenser with the nitric acid.

In the usual process, the weak and the strong acids produced are collected into separate containers, the amount of strong acid varying from 75% to 90% of the total output and varying in strength from 85% nitric acid to 93% nitric acid, depending largely upon the amount of sulfuric acid used for charging the retort and upon the length of the distillation. The weak nitric acid comprising approximately 8% to 25% of the total production, is either put back into the retort with the next charge of sulfuric acid or put through a special process to strengthen it.

The object of the present invention is to prepare comparatively strong nitric acid while using a much smaller amount of sulfuric acid than hitherto has been employed in the preparation of nitric acid of the same strength. This result I accomplish by utilizing the sulfuric acid which is used to decompose the sodium nitrate in the retort for dehydrating the vapors coming from the retort during the period when these vapors are relatively high in water and relatively low in nitric acid.

In carrying out my process, a charge of nitrate of soda is placed in a still, and there is added to this nitrate of soda ap-

proximately three-fourths of the amount of sulfuric acid which is to be used in the run. The distillation is then commenced by heating the still, and soon acid begins to come over. As previously stated, this first distillate is not very strong, and some of the sulfuric acid held in reserve is allowed to trickle in countercurrent to the uprising vapors to dehydrate them. As the distillation continues, the acid coming over becomes rapidly stronger, and as soon as it reaches the desired predetermined strength, the flow of the dehydrating acid is shut off. For some time the acid continues to come over at the given strength, but toward the end of the distillation it begins again to lack strength. The dehydrating acid is now again started and continues to run until the entire reserve amount has run into the still. As soon as all the dehydrating acid has been used up, the nitric acid coming from the still begins to drop in strength, and as soon as the strength drops below the predetermined percentage, this weaker acid is collected separately. The distillation of the weak acid is continued until the acid distilling over drops in strength to a predetermined point, when the fire is pulled from under the still. All of this dilute acid is gathered together and is mixed with three-fourths of the amount of sulfuric acid constituting the acid charge for the next run, and the entire operation is repeated.

In the attached drawing, I have illustrated diagrammatically apparatus for carrying out my process. In this drawing, 1 indicates a tank for the sulfuric acid used in charging the retort 2, with which retort the tank is connected by means of a pipe line 3. 4 represents the dehydrator comprising a suitable casing which is packed or filled with quartz ranging in size from six inches in diameter at the bottom to two inches in diameter at the top of the packing, this dehydrator having at the bottom an intake opening connected with the retort by means of a coiled duct 5 and being connected at the top by means of a duct 6 with a tank 7 containing sulfuric acid. The arrangement is such that the distillate passing from the retort through the duct 5 passes upwardly through the quartz filling toward the exhaust duct 8 leading from the top of the dehydrator, sulfuric acid at the same time being introduced in the top of the distributor from 110

the tank 7, the flow of the acid being broken up by the quartz filling of the dehydrator and presenting a large surface of sulfuric acid to the upcoming nitric gases. 5 The duct 8 communicates with a bleacher 9 of the usual well known construction, which performs the same function as the bleacher in other forms of nitric acid plants, the gases passing from the bleacher to the 10 condenser 10, where they are condensed, the condensed acid flowing back through the condenser, countercurrent to the flow of the 15 gases, then into the top of the bleacher 9 where it also flows countercurrent to the hot 20 gases passing up through the bleacher 9. From the bleacher 9, the condensed nitric acid flows out through the trap and into the cooler, both shown in the print. An outlet is provided in the cooler where the nitric 25 acid may be drawn into the container. The dehydrating acid is led from the bottom of the dehydrator through a pipe line 11 to the retort where it functions with the remainder of the acid charge in decomposing the sodium nitrate.

As a specific example of my process, I may charge the retort with any desired amount, within its capacity, of nitrate of soda, to which is added, as previously described, three-fourths of the amount of sulfuric acid which is to be used in the run, this acid being introduced from the tank 1. Since the ratio of nitrate of soda to sulfuric acid for the entire run is 1 to 1.05, I place in the still 35 787½ lbs. of 100% sulfuric acid (as 96% acid) for each 1000 lbs. of 100% nitrate of soda, and I hold in reserve one-fourth of the amount of the sulfuric acid to be employed, amounting to 262½ lbs. of 100% 40 sulfuric acid (as 96% acid). As indicated, acid of 96% strength is the actual acid used, the amount of the 90% acid being 820.3 lbs. The distillation is then commenced by heating the still, and soon 45 acid begins to come over. This acid is not very strong, and accordingly some of the 262½ lbs. of reserve sulfuric acid which is held in the tank 7 is allowed to trickle in countercurrent to the uprising vapors in the 50 dehydrator, the amount of sulfuric acid so used being approximately two lbs. per minute for each 1000 lbs. of sodium nitrate charged in the still, but varying somewhat with the strength of the nitric acid being 55 made as determined by samples and tests made during the distillation. As soon as the acid coming over from the still reaches 97% in strength, the flow of dehydrating acid is shut off and the distillation is continued in 60 this fashion until toward the end of the distillation the nitric acid distillate begins again to weaken. At this point, the dehydrating acid again is started and continues to run until all of the 262½ lbs. of reserve 65 have run into the still, at which point the

nitric acid coming from the still begins to drop in strength. As soon as the strength drops below 97%, the subsequent weaker acid is collected separately, the distillation of the weak acid continuing until the acid 70 distilling over drops to about 30 degrees Bé. in strength (41% HNO₃). The fire is then pulled from under the still, the heat of the retort still causing some distillation to go on, however, and all of this dilute acid is gathered together and mixed with the initial charge of sulfuric acid for the next run. 75

The complete operation therefore consists in charging into a retort an amount of nitrate of soda, adding to this nitrate of 80 soda substantially three-fourths of its weight of sulfuric acid, to which is mixed the dilute "ends" from the preceding distillation, and then distilling, the distillate whenever below 97% being run countercurrent to additional sulfuric acid until an additional amount of sulfuric acid equal to one-fourth of the weight of soda charged has been used up and has entered the retort. The distillate thereafter is considered as "ends", and 85 is added to the sulfuric acid in the next following run.

In the usual method of manufacturing hereinbefore described, the amount of strong acid obtained will vary from 75% to 92% 90 of the total output, and will vary in strength from 85% nitric acid to 93% nitric acid, depending on the amount of sulfuric acid used for charging the retort and upon the length of the distillation. According to the present invention, using the apparatus described, 90% to 93% of the total nitric acid made is of 97% strength, while 7% to 10% is weak, averaging 75% nitric acid. It will be noted that this weak nitric acid is put back into 100 the retort for the next distillation with no excess of sulfuric acid over and above that previously employed as the initial acid charge, so that by this method the total output of nitric acid is produced at a strength 105 of 97%, with the use of one lb. of nitrate of soda of 100% strength to 1.05 lbs. of 100% sulfuric acid as 96% strength. 110

As pointed out, my process shows substantial economies in operation, and as a further advantage, the water which otherwise would appear in the nitric acid distillate remains in the still with the sodium acid sulfate or "niter cake" left after distillation, this "niter cake" accordingly containing a 120 higher percentage of water than niter cake made in accordance with customary procedure. Under these conditions, the niter cake is more fluid and is more readily removed from the still. 125

I claim:

1. In the manufacture of nitric acid by distillation of reaction products of nitrate of soda with sulfuric acid, the process which comprises reserving approximately one- 130

fourth of the total amount of sulfuric acid used in a distillation, and passing said reserve acid into the still in countercurrent to the weak distillate.

5. 2. In the manufacture of nitric acid by distillation of reaction products of nitrate of soda with sulfuric acid, the process which comprises passing sulfuric acid prior to its participation in the reaction in countercurrent to the distillate running less than 97% nitric acid at such a rate that the resulting distillate will contain not less than 97% nitric acid.

15. 3. In the manufacture of nitric acid by distillation of reaction products of nitrate of soda with sulfuric acid, the process which comprises reserving approximately one-fourth of the entire quantity of sulfuric acid used in said reaction, and passing said reserve acid prior to its participation in the reaction in countercurrent to that portion of the distillate containing less than 97% nitric acid and at such a rate that the resulting distillate is brought to 97% nitric acid.

20. 4. In the manufacture of nitric acid by distillation of reaction products of nitrate of soda with sulfuric acid, the process which comprises starting the distillation of the nitrate of soda with substantially three-fourths of its weight of sulfuric acid, and passing a quantity of sulfuric acid approximately equal to one-fourth the weight of soda into the still in countercurrent to those portions of the distillate running below 97% nitric acid and at such a rate that the said portions of the distillate are brought to 97% nitric acid.

25. 5. In the manufacture of nitric acid by distillation of reaction products of nitrate of soda with sulfuric acid, the process which comprises starting the distillation of the nitrate of soda with substantially three-

fourths of its weight of sulfuric acid, passing a quantity of sulfuric acid approximately equal to one-fourth the weight of 45 soda into the still in countercurrent to those portions of the distillate running below 97% nitric acid and at such a rate that said portions are brought to 97% nitric acid, collecting the distillate falling in strength below 97% nitric acid following exhaustion of the strengthening acid, and adding the weak distillate to the sulfuric acid employed in the next following distillation.

6. In the manufacture of nitric acid by 55 distillation of reaction products of nitrate of soda and sulfuric acid, the process which comprises reserving 25% of the sulfuric acid employed in the reaction, running the reserve acid in countercurrent to portions of 60 the distillate falling in strength below 97% nitric acid and at such a rate that the resulting distillate will contain 97% of nitric acid, collecting those portions of the distillate following exhaustion of the reserve acid 65 which fall below 97%, and adding this collected distillate to the sulfuric acid employed in the next run.

7. In the manufacture of nitric acid by 70 distillation of reaction products of nitrate of soda and sulfuric acid, the process which comprises reserving approximately one-fourth of the sulfuric acid employed in said reaction, passing the reserve acid in countercurrent to portions of the distillate running 75 less than 97% nitric acid at such a rate that this weak distillate is brought to 97% nitric acid, collecting the distillate passing over after the exhaustion of the reserve acid which contains less than 97% nitric acid, 80 and adding this latter portion of the distillate to the said reserve sulfuric acid employed in the next run.
